Primary Examiner — Kelley A Donnelly(74) *Attorney, Agent, or Firm* — Carter, DeLuca & Farrell LLP(57) **CLAIM**

The ornamental design for a caddy, as shown and described.

DESCRIPTION

FIG. 1 is a top perspective view of a caddy in an open configuration in accordance with the present design; FIG. 2 is an exploded top perspective view thereof; FIG. 3 is a left side elevational view thereof; FIG. 4 is a right side elevational view thereof; FIG. 5 is a front elevational view thereof; FIG. 6 is a rear elevational view thereof; FIG. 7 is a top plan view thereof; FIG. 8 is a bottom plan view thereof; FIG. 9 is a bottom perspective view of the caddy of FIG. 1 in a closed configuration in accordance with the present design; FIG. 10 is an exploded bottom perspective view of the caddy of FIG. 9; and, FIG. 11 is a further exploded bottom perspective view of the caddy of FIG. 10 in accordance with the present design. The broken lines shown in the drawings illustrate portions of the caddy that form no part of the claimed design.
